UNITED STATES PATENT OFFICE.

GODFREY R. REBMANN, OF PHILADELPHIA, PENNSYLVANIA, ASSIGNOR TO
THE MORSE, WILLIAMS & COMPANY, OF PENNSYLVANIA.

DESIGN FOR AN ELEVATOR-GUIDE.

SPECIFICATION forming part of Design No. 26,289, dated November 17, 1896.

Application filed October 8, 1896. Serial No. 608,302. Term of patent 14 years.

To all whom it may concern:

Be it known that I, GODFREY R. REBMANN, of the city and county of Philadelphia and State of Pennsylvania, have invented a new and original Design for Elevator-Guides, of which the following is a specification.

My new and original design for guide-strips for elevators, &c., is illustrated in the accompanying drawing, which shows a perspective 10 view of a section of the strip.

The guide consists of a metallic strip of substantially T shape in cross-section, composed of the flanges A A and the rib B, united to the flanges by the narrow neck or web a and provided with the longitudinal grooves b. 15 I have shown but a single longitudinal groove

b on each side of the rib B; but in some cases I contemplate using more.

What I claim as new, and desire to secure by Letters Patent, is—

The design for an elevator guide-strip substantially as shown having a substantially T shape in cross-section with the rib B united to the flanges A, A, by a narrow neck a and provided with the longitudinal grooves b. 20 25

In testimony of which invention I have hereunto set my hand.

GODFREY R. REBMANN.
